UNITED STATES PATENT OFFICE.

GOODRICH Q. LEWIS, OF WHEATON, ILLINOIS, ASSIGNOR TO WILLIAM H. MINER, OF CHAZY, NEW YORK.

RAILWAY DRAFT-RIGGING.

1,232,341.

Specification of Letters Patent.

Patented July 3, 1917.

Application filed June 12, 1914. Serial No. 844,646.

To all whom it may concern:

Be it known that I, GOODRICH Q. LEWIS, a citizen of the United States, residing at Wheaton, in the county of DuPage and State of Illinois, have invented a certain new and useful Improvement in Railway Draft-Rigging, of which the following is a full, clear, concise, and exact description, reference being had to the accompanying drawings, forming a part of this specification.

This invention relates to improvements in railway draft riggings.

The object of the invention is to provide a draft rigging for railway cars of efficient construction, high capacity, and relatively few and inexpensive parts.

The invention furthermore consists in improvements in the parts and devices, and in the novel combinations of the parts and devices as herein shown, described and made the subject-matter of claims.

In the drawings forming a part of this specification, Figure 1 is a central longitudinal vertical section of a draft rigging showing one embodiment of my invention. Fig. 2 is a horizontal section taken substantially on the line 2—2 of Fig. 1. Figs. 3 and 4 are vertical sectional views taken substantially on the lines 3—3 and 4—4 of Fig. 1. Fig. 5 is a detail perspective view of the friction shell employed in my mechanism. Fig. 6 is an enlarged detail sectional view showing a portion of the wedge or spreader and one of the shoes employed in the friction mechanism.

In said drawing, the center sills or draft sills of the car are designated by the reference 10, the same having secured thereto front stops 11 and rear stops 12. Each of the stops 11 and 12 is provided with a main stop shoulder 13, a limiting stop shoulder 14, and an inner shoulder 15, the function of which will appear hereinafter. The front stops 11 are also slotted as indicated at 16, to accommodate the coupler connecting key. Mounted between the sills, and intermediate the front and rear stops, is a friction shell 17, shown most clearly in Fig. 5. The shell 17 comprises a main cylindrical portion 18 having an inner friction surface, and side walls 19—19, said side walls being forwardly and rearwardly extended as indicated at 20—20, said extensions engaging the inner shoulders 15 of the stops, whereby

the friction shell is prevented from longitudinal movement. (See Fig. 2.) To increase the strength of the shell, ribs 21 are provided on the top and bottom thereof.

Two sets of main springs 22—22 are provided in tandem arrangement, one set at each end of the friction shell, each set of springs, as shown, comprising an outer main coil 23 and an inner coil 24. Front and rear followers 25—25 are provided, and also front intermediate, and rear intermediate followers 26. Each of the followers 25—25 is formed with an annular groove 27 on its inner side, in which is adapted to be received one end of the main coil 23 of the spring, and the inner annular shoulder 28 of each of the followers forms an abutment for the inner coil of the spring. The intermediate followers are formed on their inner sides similarly to the end followers, and in addition the intermediate followers are provided with annular inwardly extending flanges 29, which, in normal position of the gear, engage the ends of a plurality of circularly arranged friction shoes 30 slidably mounted within the friction shell 17, and, as will be apparent from an inspection of Figs. 1 and 2, the shoulders 31 formed by the ends of the friction shell 18 proper, serve as the intermediate stops for the intermediate followers 26—26.

The gear is operated from the draw bar 32 by means of a tail bolt, designated generally by the reference A, said tail-bolt extending through central recesses in all of the followers, and is composed of two like parts 33, each member 33 having a main semi-cylindrical portion 34 having a shoulder 35 at the front end thereof, against which the rear end of the draw bar abuts, and a forwardly extended, slotted side wing 36 by which said tail bolt is attached to the draw bar by a coupler connecting key 37. At the rear end, each member 33 is provided with an annular groove 38 whereby the parts may be firmly locked together by a two-piece collar 39, each piece 139 of said collar having an inwardly extending annular rib 40 which engages in the annular groove 38. The members 139 are detachably secured together by means of bolts and nuts 41. It will also be observed that the collar 39 engages the rear follower 25 under draft, to thereby compress the rear set of the tandem springs.

To operate the friction shoes, of which

there are four shown in the drawing, each shoe is provided with a set of oppositely arranged wedge faces 42, and the semi-cylindrical portions 34 of the tail bolt are provided with correspondingly arranged wedge faces 43, and interposed between the wedge faces of the spreader on the tail bolt and the shoes are anti-friction rollers 44. (See Fig. 6.) The friction shell is held in position between the sills by means of the tie-plate 46, which is secured to the sills 10 by bolts and nuts 47.

In buffing, the rear shoulders 45 formed at the front end of the tail-bolt, engage the front follower 25 and compress the front set of the tandem springs, the front intermediate follower 26 being prevented from rearward movement by the friction shell 17. At the same time, the spreader formed at the center of the tail bolt A wedges the friction shoes outwardly against the internal friction shell, and moves said shoes longitudinally, and said shoes by engaging the rear intermediate follower 26 thereby compress the rear set of the tandem-arranged springs and in this connection it will be noted that not only is the movement of the front follower 25 limited by the limiting shoulders 14 on the front stops, but the rear intermediate follower 26 is also limited by the inner shoulders 15 on the rear stops 12.

Under draft, the rear follower 25 is engaged by the collar 39 to compress the rear set of the tandem springs, and the front set of said tandem springs is operated through the front intermediate follower 26 by means of the friction shoes 30, as will be understood from the detailed description of the operation under buff.

I have herein described in detail one form of my invention, but the form shown is merely illustrative, and I do not wish to be confined to the exact details shown and described, inasmuch as numerous changes and modifications will readily suggest themselves to those skilled in the art, and all such changes and modifications are contemplated as coming within the scope of the claims appended hereto.

I claim:

1. In a draft rigging, the combination with tandem arranged main springs, of a stationary friction shell intermediate said springs, friction mechanism coöperable with said shell, and means for simultaneously and directly compressing one of said springs and the other of said springs indirectly through the friction mechanism, upon either buff or draft.

2. In a draft rigging, the combination with tandem arranged main springs, of a friction mechanism located intermediate said springs, said friction mechanism including shoes and a spreader therefor, and a common member for operating both of

said tandem springs and said spreader simultaneously under draft and buff.

3. In a draft rigging, the combination with tandem arranged main springs, of a friction mechanism located intermediate said springs, said friction mechanism including friction shoes, and a tail bolt for simultaneously operating said tandem springs, said tail bolt being provided with a wedge to spread said friction shoes under both buff and draft.

4. In a draft rigging, the combination with tandem arranged springs, of a friction mechanism located intermediate said springs, said mechanism including a shell, shoes and a spreader therefor, followers for said springs, and means for moving said spreader, said shoes engaging one of the followers under buff, and engaging another of the followers under draft.

5. In a draft rigging, the combination with tandem arranged springs, front, rear, front intermediate and rear intermediate followers therefor, of a friction mechanism disposed between said intermediate followers, said friction mechanism including longitudinally movable friction shoes, said shoes being arranged to operate said intermediate followers under buff and draft, and stops for each of said followers, one intermediate follower remaining stationary under draft and the other intermediate follower under buff.

6. A draft rigging comprising, in combination, a draw bar, a tail bolt keyed to said draw bar, tandem arranged springs, followers for said springs, a friction mechanism located between the intermediate followers, said tail bolt being adapted to operate the end followers directly, and the intermediate followers indirectly by parts of the friction mechanism.

7. In a draft rigging, the combination with a draw bar, of a tail-bolt keyed to said draw bar, said tail bolt having integral wedge faces formed thereon intermediate its ends.

8. In a railway draft rigging, a tail-bolt comprising two like members, each of which has a main semi-cylindrical portion provided with a shoulder at the front end thereof, and an offset forwardly extended slotted side wing, each of said members being provided with integral oppositely arranged wedge faces.

9. A draft rigging comprising, in combination, sills having front and rear stops secured thereto, a friction shell mounted between said sills and held stationary, tandem arranged springs, one on either end of said shell, friction shoes mounted within said shell, a double-acting spreader for said shoes which forces said shoes outwardly under both buff and draft, and front, rear, front intermediate and rear intermediate

followers, the intermediate followers being operated by said shoes.

10. A draft rigging comprising, in combination, two sets of main springs, a stationary friction shell located intermediate said springs, front, rear, front intermediate and rear intermediate followers, the intermediate followers normally engaging said shell, the latter forming stops therefor, fric-

tion shoes, and a double-acting spreader 16 therefor mounted within said shell, and means for moving said followers and spreader under bluff and draft.
